(Cl. D44—1)

FIG. 1

FIGURE 1 is a perspective view of a support for lettuce or the like, showing my new design;

This is a continuation-in-part of my earlier application, Ser. No. D. 906, filed Feb. 3, 1966, now abandoned.

I claim:

The ornamental design for a support for lettuce or the like, substantially as shown and described.
